UNITED STATES PATENT OFFICE.

GEORGE HAKE, OF ST. LOUIS, MISSOURI.

GARMENT-SUPPORTER.

1,324,347.

Specification of Letters Patent.

Patented Dec. 9, 1919.

Application filed September 27, 1918. Serial No. 255,952.

To all whom it may concern:

Be it known that I, GEORGE HAKE, a citizen of the United States, and resident of St. Louis, Missouri, have invented certain new and useful Improvements in Garment-Supporters, of which the following is a specification.

This invention relates to improvements in garment supporters, and consists in the novel arrangement, construction and combination of parts, the detail and principal features of which will be hereinafter fully described and set forth in the claims.

The object of my invention is to construct a garment supporter with a rigid receiving member and a resilient supporting member, the same being so arranged as to support the garment and prevent the same from becoming detached by the movement of the person wearing the supporter.

A further object of my invention is to construct a supporter, one member of which is arranged of a rigid material such as metal and to it is attached a strip of resilient material on which is mounted a garment supporting head, the rigid material being shaped to accommodate the insertion of the head together with the garment and a receiving loop formed on the bottom of the rigid member in which the garment supporting head together with the garment is seated for properly clamping the garment between the same and preventing it from becoming detached by the regular movement of the wearer.

A further object of my invention and one of the most specific features of the invention is to provide a garment supporter with a garment supporting head having a suitable recess formed therein which properly engages with a receiving member for holding the garment in a clamped position.

Figure 1, is a front elevation of my improved invention.

Fig. 2, is a side view of the same.

Fig. 3, is a central sectional view of the same.

Fig. 4, is a detail perspective view of the garment supporting head showing the same in position on the resilient member.

Fig. 5, is a perspective view of my invention showing the same clamped to the garment.

Fig. 6, is an enlarged detail sectional view of the gripping end of the supporter show-

ing the head in its relative position with the receiving loop.

Fig. 7, is a detail perspective view of the reversed side of the receiving loop.

Fig. 8, is a detail perspective view of a portion of the receiving loop showing it in modified form.

Fig. 9, is a sectional view of the same which illustrates the loop in a partially bent position.

In the general construction of my invention and referring to the drawings in detail 10, indicates a strap of a resilient or flexible material and 11 is a receiving member constructed of a rigid material such as metal or 70 the like and which constitutes one portion of a clamping member between which the garment is properly supported.

The rigid member 11 consists of an upper elongated loop 12, through which is passed 75 the strap 10 and by said strap the member is supported. Diverging from the loop 12 is a second loop 13, through which is passed and supported the resilient member 14 of the supporter, which member is preferably 80 constructed of tape or other resilient material. Diverging from the second loop 13, are located a pair of arms 15 which are arranged on the radius of a circle and then run parallel and finally terminate into a 85 receiving loop 16. This loop consists of rectangular projections 17 with suitable bent ends 18 and a cross bar 19.

The resilient member of the support consists of the tape 14 and on the same is firmly 90 held a garment supporting head 20, consisting of an elongated rounded portion 21 with the integral base portion 22, the same provided with an elongated recess or 95 grooved out portion 23 which is located directly beneath the head 21. The base portion being of shorter diameter than the head portion 21, and this entire supporting head is firmly attached to a plate 24 by means of a central fastening member 25 in 100 the form of a rivet or the like.

The plate 24 is arranged with a pair of loops 26 through which the tape or resilient member 14 is looped for supporting the garment supporting head in its proper position.

The curvilinear portion of the inclined member is of such diameter as to freely permit the head together with the garment to pass thereover to be pressed through and 110

then pressed downwardly through the parallel sections and into the receiving loop; and when so in position the garment is firmly clamped between the bar 19 of the 5 receiving member and the recess portion of the supporting head.

The supporting head 20 previously described is preferably constructed of some soft durable material such as rubber or the 10 like, so as to prevent the cutting of the garment which is supported between the two members of the supporter.

In Figs. 6, 8, and 9, I show a modified 15 form of the supporting loop showing the same partially bent in a position different from that illustrated in the other views. But the general position of the two members of the supporter in supporting the garment will bring the outer horizontal member of 20 the supporting loop in the elongated recess of the supporting head and by this construction a garment is firmly gripped and sufficient resiliency is attained without causing the tearing of the garment and at the 25 same time prevents staining the garment by rust caused from the moisture of the body.

On account of the resilient member which 30 supports the garment supporting head, the head may be partially twisted so as to enter the rigid member with the material to which 35 it is applied, and the material may be of any thickness which when placed over the head might cause a width greater than the circumferential opening between the arms 15, and this additional thickness of the material of the garment is taken care of by 40 means of the narrowness of the base section of the supporting head, and permits the same to pass down between the parallel members, in order that the head together with the garment may properly seat itself in the receiving loop formed on the lower end of the rigid member.

Having fully described my invention what 45 I claim is:

1. A garment supporter comprising a rigid member, its upper portion formed into an elongated loop, a portion of the member ar-

ranged with projecting arms, a portion 50 thereof arranged in curvilinear form, the bottom of the arms terminating into an elongated loop, a resilient member carried by the upper loop portion of the rigid member, a cylindrical shaped garment supporting head of non-rustable material having a rectangle base and attached to the resilient member, the base of the head being of shorter length than the head proper, and said base provided with an elongated groove 60 in its front which is to receive the outer bar of said second loop.

2. A garment supporter comprising a resilient member and a rigid member, a strap supporting the rigid member, an elongated loop formed on the bottom end of the rigid member, the ends of said loop being slightly curved, an elongated rounded head of non-rustable material attached to the resilient member, said head having an integral base of shorter length than the head proper, said base provided with a groove in its front side for the reception of the outer bar of the receiving loop and between which a garment is adapted to be supported, the 70 curved ends of the bottom loop arranged to conform to the shape of the head, substantially as specified.

3. A garment supporter comprising a garment supporting head, the same consisting of an elongated rounded portion, an integral base of shorter length, said base cut away forming a groove which is located directly beneath the elongated portion and in the front in combination with a rigid member 85 having an elongated loop for the reception of the head, the outer bar of said loop designed to be seated in the groove of the base for firmly gripping and supporting the garment between the head and loop, substantially as specified.

In testimony whereof, I have signed my name to this specification, in presence of two subscribing witnesses.

GEORGE HAKE.
